UNITED STATES PATENT OFFICE.

GEORGE H. MAYNARD, OF BROOKLYN, NEW YORK.

FOLDING-BED BOTTOM.

SPECIFICATION forming part of Letters Patent No. 293,486, dated February 12, 1884.

Application filed July 18, 1883. (No model.)

To all whom it may concern:

Be it known that I, GEORGE H. MAYNARD, a citizen of the United States, residing at Brooklyn, in the county of Kings and State of New York, have invented new and useful Improvements in Folding Spring-Beds, of which the following is a specification.

This invention consists in the combination, with the slats which support the springs, of two sets of end braces and two center braces, and of sliding swivel-clasps which form a movable connection between the braces and the slats.

The peculiar and novel construction of my bed is pointed out in the following specification and illustrated in the accompanying drawings, in which—

Figure 1 represents an inverted plan when the bed is unfolded. Fig. 2 is a similar view of the bed when folded. Fig. 3 is a transverse vertical section in the plane $x x$, Fig. 1. Fig. 4 is a sectional view of one of my swivel-clasps on a larger scale than the previous figures. Fig. 5 is a detached view of one of the springs and its fastening.

Similar letters indicate corresponding parts.

In the drawings, the letters A B C D E F G designate the bottom slats of my spring-bed. These bottom slats are by preference made of hub-iron or sheet metal; but they may be made of any other material suitable for the purpose, and they serve to support the conical springs H. These springs rest upon slats with their small ends, and they are fastened in position by means of rivets a, Figs. 3 and 5. The bottom slats are connected together by a series of end braces, I K L M N O P Q R S, two center braces, T U, and by swivel-slides V, as follows: The end brace I is pivoted at its outer end to one end of the slat A and at its inner end to the inner end of the end brace K. The outer ends of the end braces K L are pivoted to one end of the slat D. The inner end of the end brace L is pivoted to the inner end of the end brace M, and the outer end of this last-named end brace is pivoted to one end of the slat G.

On the brace I is secured a swivel-slide, V, which embraces the slat B, and on the brace K is secured a similar swivel-slide V, which em-

braces the slat C. On the braces L M are also secured similar swivel-slides V, one of which embraces the slat E and the other the slat F. The construction of these swivel-slides will be understood by referring to Fig. 4. Each of them is composed of a piece of sheet metal, v, the ends of which are bent in the form of the letter U, while from its center extends a pivot, v', which swivels in the braces T—for instance, the brace T to which said swivel-slide is attached. The slat G fits between the U-shaped ends, so that the swivel-slide can move on said slat, while it is free to turn on its pivot in order to accommodate itself to the varying position of the brace to which it is attached. The center brace T is pivoted to the end of the slat A opposite to that to which the end brace I is pivoted, and said center brace connects with each of the slats B C D E F G, respectively, by means of a swivel-slide V, constructed as above described. The center brace U is pivoted to the end of the slat G opposite to that to which the end brace M is pivoted, and it (said center brace) connects with each of the slats F E D C B A, respectively, by means of a swivel-slide V.

The two center braces, T U, are connected at about the middle of their length by means of a pivot, b. The end brace N is pivoted at its outer end to slat B and at its inner end to the center brace T. The end brace O is pivoted at its outer end to the slat C and on its inner end to the end brace P. The end brace P is pivoted at its outer end to the slat D and at its inner end to the center brace T, and it carries a swivel-brace V, which embraces the slat C. The end brace Q is pivoted at its outer end to the slat D and at its inner end to the center brace U, and it carries a swivel-slide V, which embraces the slat E. The end brace R is pivoted at its outer end to the slat E and at its inner end to the end brace Q. The end brace S is pivoted at its outer end to the slat F and at its inner end to the center brace U.

On the bottom slat A are secured two elastic brackets, A' A², which support the top slat X, and on the bottom slat G are secured two similar brackets, G' G², which support the top slat Y. The form of the brackets A' A² G' G² is shown in Fig. 3, and since the top slats X

Y are secured to the outer upper ends of said brackets, an elastic or yielding support is provided for said top slats. The springs H, which are connected at their bottom ends to the slat 5 A, are secured at their upper ends to the slat X, and the springs which rest upon the slat G are connected at their upper ends to the slat Y.

Between the bracket A' and the slat A is placed a distance-piece, a', (see Fig. 4,) so that the swivel-slide V at the end of the center brace U can pass beneath said bracket, and the bracket G' is mounted in the same manner to allow the swivel-slide V at the end of the center brace T to pass beneath it, such being requisite in order to be able to fold up the spring-bed to the position shown in Fig. 2. The springs H are also mounted in such a manner that the swivel-slides V can move past them.

When the bed is unfolded, as shown in Fig. 1, it is retained in position by the center braces T U and the end braces N O P Q R S, and it can only be folded by pressing against those 25 ends of the slats A G to which the center braces T and U are pivoted.

If desired, the end braces N O R S may be omitted.

The end braces I K L M are applied to im- 30 part steadiness to that end of the bed on which they are situated.

What I claim as new, and desire to secure by Letters Patent, is—

1. The combination, with the bottom slats

and with the springs mounted thereon, of the 35 center braces T U, crossing each other and pivoted to the outer slats on opposite sides, and connected to the intermediate slats by the swivel-slides V, the end braces P and Q, connected at one end to the center slat and at the 40 other end to the center braces T U, and the end braces I K L M, for holding the opposite ends of the slats in position, substantially as described.

2. The combination, with the bottom slats 45 and with the springs mounted thereon, of the brackets A' A' G' G', the top slats X Y, the center braces T U, and the end braces I K L M, the braces being connected with the slats, and the several parts constructed and ar- 50 ranged substantially as described.

3. The combination, with the bottom slats and with the springs mounted thereon, of the 55 center braces T U, pivoted to the outer slats on opposite sides and connected to the intermediate slats by the swivel-slides V, the end braces P and Q, connected at one end to the center slat and at the other end to the center braces T U, and the end braces I K L M, for holding the slats in position at the opposite 60 end, substantially as described.

In testimony whereof I have hereunto set my hand and seal in the presence of two subscr- 65 ing witnesses.

GEORGE H. MAYNARD. [L. S.]
